UNITED STATES PATENT OFFICE.

CHARLES W. PALMER, OF PHILADELPHIA, PENNSYLVANIA, ASSIGNOR TO
FRANK H. CAVEN AND JAMES CAVEN, OF PHILADELPHIA, PENNSYLVANIA, TRADING UNDER THE FIRM, STYLE AND TITLE OF JAMES CAVEN & SON.

MACHINE FOR GRADING SAND.

No. 800,480.

Specification of Letters Patent.

Patented Sept. 26, 1905.

Application filed June 4, 1904. Serial No. 211,198.

To all whom it may concern:

Be it known that I, CHARLES W. PALMER, a citizen of the United States, residing in Philadelphia, Pennsylvania, have invented certain 5 Improvements in Machines for Grading Sand, of which the following is a specification.

One object of my invention is to provide an improved machine for grading fine granular material, such as sand, and which shall be 10 capable of delivering a product containing any desired percentages of particles of different sizes.

A further object of the invention is to provide an efficient and inexpensive machine for 15 continuously removing from granular material all particles less than a certain predetermined fineness.

These, together with other advantageous results, I attain as hereinafter set forth, reference being had to the accompanying drawings, in which—

Figure 1 is a side elevation, to some extent diagrammatic, illustrating one arrangement of apparatus for grading sand according to 25 my invention. Fig. 2 is a side elevation, partly in section, of one of the separating-hoppers employed in connection with my invention, the same being illustrated as provided with two sets of upwardly-pointing nozzles 30 instead of one set, as in the hoppers shown in Fig. 1. Fig. 3 is a plan view of the piping for the sets of nozzles, known as the "agitator," employed in carrying out my invention. Fig. 4 is a plan view, to some extent diagrammatic, showing an arrangement of apparatus for returning a certain proportion of fine material to the finished product; and Fig. 5 is a side elevation of the apparatus shown in Fig. 4.

Hitherto great difficulty has been experienced in grading fine granular material, such as sand, in commercial quantities—that is, in separating a given body of sand into masses of definite degrees of fineness. It will be understood that it is frequently desirable 40 to procure a body of sand which, for example, shall be of a certain fineness or which shall contain definite and predetermined percentages of particles of different fineness, and this has hitherto been commercially impossible, 45 owing to the difficulty of treating large bodies of sand at any but a cost which would be prohibitive. The objection to accomplishing this 50 end by the use of screens is due principally to

the fact that the meshes of the screens become very quickly clogged, particularly when the 55 material treated is of a fineness ranging from a size which would pass a No. 10 sieve and be retained upon a No. 80 sieve.

I have found it possible to grade sand, even of the finest, in any desired manner by exposing the same to the action of a current of water whose pressure and velocity could be so varied as to carry away all material finer than a certain definite size, the sand being subjected to treatment in one or any desired 60 number of receptacles in order to satisfactorily accomplish this end. If it is desired that there shall be a certain proportion of fine material in a certain body of sand, I provide means whereby some of the fine material removed at the beginning of the operation is returned to the sand at another period of its treatment.

In carrying out my invention I prefer to employ the apparatus shown in Fig. 1, in 75 which A represents a receiving-hopper placed to discharge its contents into a conveyer B, which transfers the sand or other material treated to a slide or chute b. Said conveyer and a large portion of the apparatus hereinafter 80 described is carried upon a framework A', which supports a rotary double screen C, into which the chute b discharges. A water-supply pipe b' is placed to deliver water upon this chute, so as to facilitate the flow of sand 85 into the inner rotary screen c', which forms a part of the screen C. A chute c' receives material delivered from the interior of the rotary screen c, while a chute c" receives that delivered from the screen C, the finer particles 90 which pass through said latter sieve falling upon a slide or chute c", which in turn delivers material upon a chute c'. This latter discharges the sand into the first of a series of hoppers D D', &c., preferably of the construction illustrated in Fig. 2, and provided with a weir or overflow edge d, as indicated in Fig. 1. Each of the hoppers has attached to its lower portion a discharge-pipe d', provided with a contracted throat d² and a nozzle d³, connected to a supply-main d⁴ and placed so as to deliver a jet of water into said throat d². Supported at a slight distance above the bottom of each hopper are one or more series of upwardly-pointed nozzles d⁵, projecting from a U-shaped pipe connected to a

conduit d^6 of suitable size, and it will be noted that said pipe for the nozzles is preferably arranged around or adjacent to the sides of the hopper, so as to permit of the downward passage of sand between its arms. The pipe d' from the hopper D is extended upwardly, so as to discharge into the top of the hopper D', and the pipe d^7 from this latter hopper in turn discharges into the hopper D². A hopper D³ receives material from the discharge-pipe a^8 of the hopper D², and there is a conveyer E for removing the sand from said first hopper to any desired chute (not shown) for delivery to a stock-pile or to any receiving vessel.

15 While in Fig. 2 I have shown the supply-pipe d^6 to the agitators extending upwardly through the hopper and over its edge, it may, if desired, be extended through the side of the hopper, and all of these pipes d^6 are connected 20 to a supply-main f , which in turn is supplied with water from a pump F. The jet-supply pipes d^4 are connected to a supply-main g , to which water is delivered from a pump G.

Under operating conditions sand is taken 25 from the hopper A by the conveyer B and is delivered to the interior screen c. Foreign matter, such as roots or large stones, &c., passes from this screen to the chute c', while the material passing through this screen is 30 still further divided, since part of it passes through the finer screen C, while another portion passes off into the chute c². It will be understood that water is constantly furnished to these screens from the pipe b', so that material capable of passing a No. 10 screen, for instance, is delivered upon the chutes c³ and c⁴ and flows freely into the hopper D. Water is continuously delivered under pressure in this and in the two other hoppers D' and D² 35 by means of the agitators formed by the various upwardly-discharging nozzles d⁵, and as this water passes away from the hopper over the weir d it carries with it the mud and a certain proportion of the dust or very finest 40 particles found in the sand. The heavier particles sink to the bottom of the hopper, where they are propelled by a jet of water delivered from the nozzle d⁹ through the pipe d' and discharged into the hopper D'. In this second 45 hopper the water delivered by the agitator may, if desired, be at a higher pressure than that delivered by the agitator in hopper D, as determined by the amount of opening of a valve d⁹ in the pipe d⁶, so that a still 50 further portion of the fine material in the sand will be carried away by the overflow-water from this second hopper, while the remainder is propelled by the water-jet at the bottom of the hopper through the discharge-pipe d⁷ and is delivered to the hopper D². Here again it is subjected to upwardly-discharging jets of an agitator, which, as before, may deliver water at a higher pressure 55 than that in the other hoppers or, if desired, may be at the same pressure. In any case

a still further amount of fine material, of a larger grade, however, than before, will be separated from the sand as it falls to the bottom of the hopper, and this latter is finally delivered into the hopper D³, from whence it 70 is taken by the conveyer E. By throttling the water delivered to the agitators or by varying the pressure of the water in the main f by suitably governing the pump F material of any desired grade may be separated 75 from that passing through the various hoppers and afterward returned to the hopper D³, so that the sand in said hopper can be made to contain any desired proportion of particles of various sizes—that is, it will consist of 80 sand small enough to pass the screen C and having any desired proportion of relatively fine particles.

It will be understood that, if desired, the exceedingly fine material carried away by the 85 overflow of water from any one or a number of the hoppers D, &c., may be saved for use by itself or for future mixture with sand of other grades, the particular case illustrated in Fig. 1 being one in which the finest grade 90 of material is not desired for use.

In order to obtain a product composed of a mixture of relatively coarse and relatively fine sand which shall be free of intermediate sizes of material, I preferably employ the arrangement of apparatus shown in Figs. 4 and 5, in which the hoppers D, D', and D² are provided with troughs m, m', and m², respectively, for the reception of water escaping from said hoppers. These troughs all discharge into a waste-chute m³ and in addition have each a gate or valve m⁴ opening into a chute m⁵, which discharges into a hopper m⁶. This latter is provided with a water-jet conveyer m⁷, similar to that used in connection with the hoppers D, &c., and by said conveyer material is delivered into the hopper D³. Under operating conditions three different grades of material are discharged by the three hoppers D, D', and D² through the 100 troughs m, m', and m² into the chute m³, while a fourth grade, composed mostly of coarser material, is delivered into the final hopper D³. If now it is desired that the finished product shall contain a larger percentage of very 105 fine material than would be the case under ordinary conditions, the gate m⁴ is opened, so that the water overflowing from the hopper D is delivered into the chute m⁵, and since this water carries with it a large proportion 110 of the very fine material contained in the sand delivered from the screen C said material after passing to the hopper m⁶ is discharged into and mixed with the finished product in the hopper D³. It is obvious that 115 the amount of this fine material so added may be very closely regulated by means of the slide or gate m⁴ and also that various proportions of coarser material may be similarly added by suitable manipulation of the gates 120

125 130 135

m^4 in the troughs m' and m^2 . If desired, water-jets m^3 may be employed to facilitate the flow through the trough m^5 .

Instead of regulating the pressure of water delivered by the agitators to vary the grade of material carried away by the water in any one of the hoppers I may attain the same end by adjusting the heights of the various weirs d^{10} , as illustrated in Fig. 1. On the other hand, there may be more than one set of agitators to each hopper—for example, as shown in Fig. 2, where the second set of nozzles d^8 are arranged around the sides, so as to increase the violence of the water action on the sand under treatment.

I claim as my invention—

1. The combination of a series of containers each having a conduit for liquid overflowing therefrom, means for conveying material from the bottom of each container and discharging it into another container, a receptacle for the finished product, a conduit connecting the overflow-conduits with said receptacle, and another conduit connecting the lower portion of the last container of the series with the receptacle, with adjustable means

for directing the material from the overflow-conduit of any container into the conduit to said receptacle, substantially as described.

2. The combination of a series of containers each having a conduit for liquid overflowing therefrom, means for conveying material from the bottom of each container and discharging it into another container, a receptacle for the finished product, a conduit connecting the overflow-conduits with said receptacle, another conduit connecting the lower portion of the last container of the series with the receptacle, hydraulic means for causing flow of liquid through said last conduit, means for separately discharging the grades from the containers, and adjustable means for diverting any number of said grades from the overflow-conduits to the conduit connecting with said receptacle, substantially as described.

In testimony whereof I have signed my name to this specification in the presence of two subscribing witnesses.

CHARLES W. PALMER.
